UNITED STATES PATENT OFFICE.

BERTON H. SILLS, OF TORONTO, ONTARIO, CANADA.

DESIGN FOR A FRONT GLASS FOR AUTOMOBILE-HEADLIGHTS.

53,667.

Specification for Design.

Patented July 29, 1919.

Application filed December 5, 1917. Serial No. 205,674. Term of patent 7 years.

To all whom it may concern:

Be it known that I, BERTON H. SILLS, of the city of Toronto, in the county of York, Province of Ontario, Canada, a subject of the King of Great Britain, have invented a new, original, and ornamental Design for a Front Glass for Automobile-Headlights, of which the following is a specification, reference being had to the accompanying drawings, forming part thereof, in which—

Figure 1 is a front elevation of a front glass constructed in accordance with my design, and

Fig. 2 a cross section of the same.

I claim—

The ornamental design for a front glass for automobile headlights as shown.

Signed at Toronto, Canada, this 20th day of November, 1917.

BERTON H. SILLS.
